DESIGN FOR A CASING FOR SOUND APPARATUS

David C. Rockola, Chicago, Ill., assignor to Rock-Ola Manufacturing Corporation, Chicago, Ill., a corporation of Delaware

Application February 5, 1941, Serial No. 98,748

Term of patent 3½ years

To all whom it may concern:

Be it known that I, David C. Rockola, a citizen of the United States, residing at Chicago, in the County of Cook and State of Illinois, have invented a new, original, and ornamental Design for a Casing for Sound Apparatus, of which the following is a specification, reference being had to the accompanying drawings, forming a part hereof.

Fig. 1 is a front perspective view of a casing for sound apparatus showing my new design;

Fig. 2 is a rear elevational view;

Fig. 3 is a top plan view.

I claim:

The ornamental design for a casing for sound apparatus, substantially as shown.

DAVID C. ROCKOLA,
